UNITED STATES PATENT OFFICE.

FRED R. BARBOUR, OF LOS ANGELES, CALIFORNIA.

TENT.

Application filed January 25, 1926. Serial No. 83,597.

This invention relates to and has for a main object the provision of an improved, simple and economical form of tent and support structure therefor, capable of being 5 quickly collapsed and assembled for supporting a tent in operative or inoperative position.

Another object is to provide in a collapsible tent structure a unitary tent covering of 10 fabric, free from guys, ropes, cords or other reinforcing elements, and adapted to be supported solely by means of a single central pole and collapsible cross arms arranged horizontally at the top of said pole, and at 15 two opposite sides of the tent so as to provide a rigid structure when the lower edge of the tent is staked to the ground.

A further object is to provide at the top 20 of the tent horizontal seams at the junction of the top and sides, and sectional rods held in said seams, a sectional pole in the center of the tent, and a sectional cross arm on the top of said pole connected at the ends with said sectional rods for supporting the tent 25 rigidly in position.

Still other objects may appear as the description progresses.

In connection with the improvements named herein, reference is had to my issued 30 Patent No. 1,531,473 dated March 31, 1925, over which the present invention has several advantages and improvements.

In the accompanying drawings I have shown a preferred structure, subject to 35 change and modification within the scope of the appended claims without departing from the spirit of my invention.

In said drawings:

Fig. 1 is a sectional elevation of a tent 40 embodying my improvements.

Fig. 2 is a fragmentary side elevation of the same.

Fig. 3 is a fragmentary sectional elevation 45 of the same as viewed from a plane at right angles to Fig. 1.

Fig. 4 is an enlarged fragmentary view of the supporting structure detached from the tent and partly in section.

Fig. 5 is a section of the same on line 5— 50 5 of Fig. 4; and

Fig. 6 is a section of the same on line 6— 6 of Fig. 4.

Fig. 7 is an enlarged view of the reinforcing bars employed at the two opposite sides 55 at the top of the tent.

Fig. 8 is a fragmentary section of the top of the tent, showing means for supporting one of the eave supporting rods.

In a preferred form my tent includes a tent of somewhat conventional form as at 60 T, which has a front 1, a rear portion 2, sides 3 and 4, and a top section 5 all integrally formed of the usual tent fabric, sewed together and provided at its bottom edge with a plurality of staples 6, 6, etc., by means of which the tent T may be attached to the ground by means of the stakes 7, 7, etc.

It will be observed that the sides 3 and 4 are cut on arcuate lines 8—8 at the junction with the top 5, so that said top will be pitched and of concave form, gradually increasing in depth from the corners 9, 9 downwardly to the junctions with the sides 3 and 4, thus providing means for draining water from the ridge 10 of the tent.

The tent is supported solely on a single pole P, which consists of two or more sections as at 11 and 12, with abutting ends, and having the joint therebetween covered by an elongated metallic sleeve 13, with a plurality of perforations 14, 14, therein adapted to receive a pin 15 so that the pole P may be lengthened for stiffening the tent by placing the pin 15 in different perforations 14.

At the top of the pole P, I provide a sectional cross arm A composed of a pair of mating sections a and a' in the same horizontal plane, and a bar B underlying the inner ends of said sections. The bar B has a central bore 16 adapted to receive the pin 17 carried in the upper end of the pole P, and said bar B and the two inner ends of the arms a and a' are adapted to be encompassed by a metal cuff C of rectangular cross section as shown in Figs. 4 and 5.

The arm a and the bar B are permanently secured to one end of said cuff by means of a bolt 18. The arm a' on the other hand is removably held in the cuff C and is removably attachable to the bar B, so that when the tent supporting structure is collapsed a more compact package may be made of the several sections. Bar B is also additionally attached to cuff C by means of a bolt 19, and one end of said bar is substantially extended from the cuff C so as to form an elongated support for the removable arm a'.

When positioned as shown in Fig. 4 the inner end of arm a' is extended inwardly in the cuff C into abutting relation with a pin 110

20, which is a temporary expedient held in the cuff for limiting the inward movement of arm a' . The outer end of arm a' is detachably secured to bar B by means of the right 5 angularly bent strap 21 which, as shown in Fig. 6, has trunnions 22, 22 bent inwardly into recesses in the arm a' , and depending portions 23, 23 which connect said trunnions with the portion 21 adapted to underlie the 10 bar B. This strap 21 is adapted to swing on the arm a' into and out of position with respect to the bar B. Thus, when the three 15 sections of the cross arm A are fitted together as shown and described, a unitary rigid structure is provided on the top of the pole for holding the sides 1 and 2 of the tent stretched apart.

The outer ends of arms a and a' are provided with metal strips 24, 24 which have 20 hooks 25, 25 bent downwardly and outwardly therefrom, and adapted to receive and hold a pair of horizontal bars R, R, which are adapted to be carried in seams 26, 26 at the top of the tent, and at the junctions between 25 the sides 1 and 2 of the top 5.

After the tent has been for some time in use and subjected to the action of the elements, the fabric material of which the tent is made will ultimately shrink, so that the 30 length of the cross arm A will necessarily be shortened to a corresponding extent, and said cross arm A may be shortened to accommodate this shrinkage by removing the pin 20 in the cuff C so that the inner end of arm a' will move inwardly into the cuff in abutting relation with the inner end of the arm a .

The rods R, R, as shown in Fig. 7, are composed of preferably two sections, r and r' , with their inner ends in abutting relation 40 and enclosed in an elongated metallic sleeve S, said sleeve being positioned in the center of the tent, and the seams 26 being open for a short distance on either side of the joint between said sections so as to permit the 45 engagement of the hooks 25 of straps 24 with the sleeves S.

The tent is erected and assembled in the following manner. First, the tent T is placed on the ground and the four corners 50 thereof positioned so that the tent will form a perfect rectangle and the four sides thereof will be squared with each other, after which the corner stakes 7 are driven through the eyelets or straps 6 into the ground. Thereafter the rod sections r and r' are moved into 55 abutting position with the joints therebetween covered by the sleeves S. The cross bar A is then assembled, the small arm a' being secured in the cuff C and to the bar B, as hereinbefore described, and the assembled 60 arm A is then moved so that the hooks 25 on each end thereof will underlie the sleeves S, S of the arms R, R. The pole P having previously been assembled, is then moved 65 into position beneath the cross arm A and

the pin 17 on the upper end thereof inserted in the bore 16 of bar B. The pole is then moved from an angular position into a vertical position beneath the arm A, and the pin 15 inserted in one of the perforations 14 70 in sleeve 13, so that the pole will be sufficiently long to hold the tent in rigid position and stretched to a maximum or desired extent. Thereafter, other stakes 7 intermediate the corners may be driven into the 75 ground and the tent will be in readiness for use.

In collapsing the tent the operation is the reverse. Pole P is first removed and the sections 11 and 12 thereof detached from the 80 sleeve 13, then the cross arm A is removed and the sections a and a' detached. Thereafter the sleeve S is moved in one or the other directions over one or the other sections r and r' so as to disengage said sections, but the sections r and r' are not removed from the 85 seams 26 of the tent. As a final operation the tent T is then pulled in a given direction against the stakes and then in an opposite direction for strengthening the 90 sides, and the top portion is then folded back over the ground, after which the stakes are removed and the tent T, which will then be in a rectangular form on the ground, may be folded into compact form and the sections 11 and 12 of the pole P and the arms 95 a and a' and B of the cross arm may be rolled in the bundle formed by the tent T.

What I claim is:

1. A tent structure including a rigid cross arm composed of an elongated bar, an arm permanently secured to a portion of said bar, an arm detachably secured to an opposite portion of said bar, and a metallic cuff secured to said bar and encompassing the 100 ends of said arms.

2. A tent structure including a rigid cross arm composed of an elongated bar, an arm permanently secured to a portion of said bar, an arm detachably secured to an opposite portion of said bar, a metallic cuff secured to said bar and encompassing the 105 ends of said arms, and means on said detachable arm for detachably connecting the same with a portion of said bar.

3. A tent structure including a rigid cross arm composed of an elongated bar, an arm permanently secured to a portion of said bar, an arm detachably secured to an opposite portion of said bar, a metallic cuff secured to said bar and encompassing the 110 ends of said arms, and metallic straps on the outer ends of said arms for the purpose described.

4. A tent structure including a vertical pole, a horizontal bar detachably held on the upper end of said pole, an arm horizontally extended from a portion of said bar and permanently secured thereto, an arm extended from an opposite portion of 115 120 125 130

said bar and detachably secured thereto, and a sleeve secured to said bar and enclosing the inner end of said arm.

5. A tent structure including a rigid cross arm composed of an elongated bar, an arm permanently secured to a portion of said bar, an arm detachably secured to another portion of said bar, a sleeve secured to said bar and encompassing the ends of said arms, 10 a pair of rods disposed in parallelism at the ends of said bars, and means on the ends of said bars for supporting said rods.
6. A tent structure including a rigid cross

arm composed of an elongated bar, an arm permanently secured to a portion of said bar, 15 an arm detachably secured to another portion of said bar, a sleeve secured to said bar and encompassing the ends of said arms, a pair of rods disposed in parallelism at the ends of said bars, means on the ends of 20 said bars for supporting said rods, and a pole detachably connected with said cross arm for supporting all of said members in operative position.

FRED R. BARBOUR.
